UNITED STATES PATENT OFFICE.

SETH B. ATWOOD, OF ROCKFORD, ILLINOIS.

DOOR BUFFER.

1,403,665.

Specification of Letters Patent. Patented Jan. 17, 1922.

Application filed January 3, 1921. Serial No. 434,437.

To all whom it may concern:

Be it known that I, SETH B. Atwood, a citizen of the United States, residing at Rockford, in the county of Winnebago and State of Illinois, have invented new and useful Improvements in Door Buffers, of which the following is a specification.

This invention relates to door buffers, and while capable of general application, a buffer in accordance with my present invention is particularly adaptable for use on automobile bodies.

One of the primary purposes of my invention is to provide a buffer which can be made economically of sheet metal, and which can be readily applied to the door jamb by simply sliding it into a socket provided therefor by drilling a circular hole of shallow depth into the face of the door jamb.

Another object of the invention is to provide a buffer, the metal body of which when installed on a door, will completely cover the space or opening surrounding the same, resulting from the circular contour of the socket in which the rectangular buffer body is disposed.

A further object is to manufacture the buffer body from a single piece of sheet metal, which, when stamped and pressed in accordance with my improved method, forms a body of the requisite size and contour adapted to receive the rubber buffer which may be slipped into place in the undercut socket or groove provided in the metal body portion.

Other objects and many of the attendant advantages of this invention will be readily appreciated as the same becomes better understood by reference to the following description when considered in connection with the accompanying drawings.

Referring to the drawings:

Fig. 1 is a plan view of the metal blank from which my improved buffer body is formed;

Fig. 2 is a face view of the body member after the stamping operation;

Fig. 3 is an edge view of the partially formed body shown in Fig. 2;

Fig. 4 is a view similar to Fig. 2, showing the body after the expanding operation;

Fig. 5 is an edge view of the body formed as shown in Fig. 4;

Fig. 6 is a face view showing the application of the buffer to a door jamb;

Fig. 7 is an edge view of the same;

Fig. 8 is a sectional view on the line 8 of Fig. 6.

In the practice of my method, by which my novel buffer is produced, a piece of sheet metal is first stamped out into the shape shown in Fig. 1, forming a flat blank 11 of metal, having rounded rear corners 12, and tangs or projections 13 at the forward corners, which, as will be apparent from Fig. 1, are tapered at their inner edges from their bases toward their outer ends. The same operation which stamps out the metal blank also forms a countersunk screw hole 14, positioned as illustrated.

This blank is then subjected to the operation of a pair of dies which depress the central portion of the blank forming a socket 16, in the center of which is disposed the screw hole 14, the socket having straight side walls 17 and a straight rear wall 18, all as shown in Fig. 3. The tangs 13 are also by the same operation bent downwardly at the front edge of the body, as will be apparent from Figs. 2 and 3.

The next step is to provide undercut side walls for the socket 16 by expanding the lower portions thereof. This is accomplished by inserting endwise into the socket from the front end thereof a tool, the sides of which are inclined so that the side walls 17 are forced outwardly at their lower ends into the position indicated in Figs. 4 and 5. When thus positioned, the inclined inner edges of the tangs 13 lie flush with the inner faces of the walls 17, and these tangs provide a front for the body, having straight outer edges and inclined inner edges formed to the inclination of the side walls 17.

The body thus formed is now adapted to be applied to the door jamb of an automobile body. Such a jamb is indicated by reference character 19 in Figs. 6, 7 and 8, and the surrounding flange 21 projecting laterally on three sides of the socket 16 enables a round socket, indicated by reference character 22, to be bored into the face of the

jamb, thereby eliminating the chiseling and incident labor and expense necessary to produce a rectangular socket, such as is customarily necessary for the reception of buffers of this general type. The round socket is produced by simply boring a shallow hole into the face of the door jamb, the center of the hole being coincident with the center of the screw hole 14 when the metal body portion of the buffer is positioned in the socket. It will be observed from Fig. 6 that the socket is so disposed that it is intersected by the shoulder 23 of the door jamb, this arc being of approximately the width of the socket 16 of the buffer body, so that by breaking out a small portion of the wood wall to conform to the inclination of the walls 17, the body may be slid into position in the socket from right to left, viewing Fig. 6. It will be observed that the rear corners of the socket 16 engage at two points with the perimeter of the socket 22 and that the flange 21 overlies and completely covers the annular portions of the socket 22 which are not filled by the metal body.

When the body has been slipped into position, as described, a screw 24 is inserted through the screw hole 14 and screwed into the door jamb 19, thus securely fastening the body in position. The rubber buffer portion 25, which consists of a rubber block having inclined side walls conforming to the inclination of the walls 17 of the metal socket, is then slipped into position from the open end of this socket so that its outer edge projects beyond the metal of the body, as shown in Figs. 6 and 8 in position to be engaged by the flange or rib 26 of the door 27 when the door is in closed position, as shown in Fig. 8. This buffer block, which is inserted into the metal body under a slight compression, will be retained in position by its resiliency.

It will be apparent that I have provided a door buffer, the body portion of which is composed of a single piece of sheet metal stamped to shape so that it provides an undercut socket for the reception of the rubber buffer block, also provides a marginal flange which enables the body to be used in a circular socket, thus obviating the necessity of cutting out a rectangular socket in the door jamb. Furthermore, the tangs or lips which are bent down at the forward edge of the body, form a metal face at each side of the buffer block which covers the rough edges of the socket formed in the wooden jamb, and gives a finished appearance to the completed buffer.

It is believed that the construction of a door buffer embodying my invention and the method of producing the same will be understood from the foregoing without further description, and it should be also manifest that the structural details of the buffer

itself, as well as the various steps employed in its manufacture, are capable of considerable modification within the scope of the invention as set forth in the following claims.

I claim:

1. A door buffer, comprising a metal body having an undercut socket open at its front face and at one end to receive a buffer block and also having a marginal flange projecting outwardly in the plane of said front face beyond the metal forming the walls of said socket, and a buffer block disposed in said socket.

2. A door buffer, comprising a sheet metal body formed to provide a depressed socket having a circumferential flange partially surrounding the same, and lips disposed at right angles to said flange adjacent the open end of said socket.

3. A door buffer, comprising a body formed of sheet metal providing a depressed socket having upwardly converging side walls, an outwardly projecting flange disposed around three sides of said socket, and lips forming a continuation of said flange but disposed at right angles to the plane of the flange to form closures adjacent the open end of said socket.

4. A door buffer, comprising a sheet metal body bent to provide a depressed socket open at one end and having inclined side walls, a flange extending outwardly from the upper edges of said socket, front walls disposed at each side of the open end of said socket and closing the spaces between the outer faces of said side walls and said flanges, and a resilient buffer block disposed in said socket and projecting outwardly from the open end thereof.

5. The combination with a door jamb provided with a circular socket, of a buffer body having a rectangular socket disposed in said circular jamb socket, and a flange overlying the space of said jamb socket unoccupied by the buffer body, and a resilient buffer block disposed in said body socket.

6. The combination with a door jamb provided with a circular socket, of a buffer body comprising a rectangular portion seated in said socket and a flange portion overlying the marginal portions of said socket outside the rectangular portion, and a resilient buffer block disposed in said rectangular portion.

7. The combination of a door jamb provided with a socket open at one side and having a curved wall at that side opposite said opening, of a buffer body comprising a rectangular portion seated in said socket and having a flange overlying and covering the space between said body and the socket walls, and a resilient buffer block disposed in said body.

8. A door buffer, comprising a body formed to provide a depressed open faced socket having upwardly converging side

walls and an outwardly projecting marginal flange extending from the upper edges of the walls of said socket, the socket being open at one end to accommodate a buffer block, 5 and a resilient buffer block disposed in said socket.

9. A door buffer, comprising a metal body

provided with a depressed socket open at one end, a circumferential flange projecting outwardly from the upper edges of said 10 socket, and front walls perpendicular to the plane of said flange at each side of the open end of said socket.

SETH B. ATWOOD.
